LIPSTICK CONTAINER

Leonard Henry Salisbury, Vancouver,
British Columbia, Canada

Application May 31, 1946, Serial No. 130,301

Term of patent 3½ years

(Cl. D86—10)

To all whom it may concern:

Be it known that I, Leonard Henry Salisbury, a citizen of the Dominion of Canada, residing at Vancouver, in the Province of British Columbia, Dominion of Canada, have invented a new, original, and ornamental Design for a Lipstick Container, of which the following is a specification, reference being had to the accompanying drawing, forming part thereof.

Fig. 1 is a perspective view of a lipstick container showing my new design, the side not seen corresponding in design to the side shown.

Fig. 2 is a side elevational view of the lipstick container with the closure removed;

Fig. 3 is a side elevational view of the closure.

I claim:

The ornamental design for a lipstick container, as shown and described.

LEONARD HENRY SALISBURY.
